Primary Examiner — Susan Bennett Hattan*Assistant Examiner* — Marie Fast Horse(74) *Attorney, Agent, or Firm* — Cantor Colburn LLP(57) **CLAIM**

We claim, the ornamental design for a telephone, as shown and described.

DESCRIPTION

FIG. 1 is a front perspective view of a telephone showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another side view thereof, in which the telephone is shown in another position;

FIG. 9 is another side view thereof, in which the telephone is shown in another position showing the base portion detached, rotated 180 degrees, and reattached to the opposite inclined surface; and,

FIG. 10 is another front view thereof, in which the telephone is shown in a module inclusive environment.

The broken lines illustrating portions of the telephone are for environmental purposes only and form no part of the claimed design.

1 Claim, 6 Drawing Sheets(56)
